UNITED STATES PATENT OFFICE.

PAUL M. HENGSTENBERG, OF WILKINSBURG, PENNSYLVANIA, ASSIGNOR TO WESTINGHOUSE ELECTRIC & MANUFACTURING COMPANY, A CORPORATION OF PENNSYLVANIA.

CONNECTOR.

1,374,566.

Specification of Letters Patent. Patented Apr. 12, 1921.

Application filed March 11, 1919. Serial No. 281,957.

To all whom it may concern:

Be it known that I, PAUL M. HENGSTENBERG, a citizen of Germany, and a resident of Wilkinsburg, in the county of Allegheny and State of Pennsylvania, have invented a new and useful Improvement in Connectors, of which the following is a specification.

My invention relates to connectors and 10 particularly to connecting devices for joining electrical conductors.

One object of my invention is to provide a device of the above indicated character that shall be simple and durable in construction, economical to manufacture, easy 15 to manipulate and effective in operation.

Another object of my invention is to provide a connector that shall permit different numbers of conductors to be variously connected. 20

Another object of my invention is to provide a connector that shall have means for securely wedging a conductor thereagainst and resilient means for moving the wedging 25 means.

A further object of my invention is to provide a connector that shall be provided with longitudinal grooves and have readily-removable means for securely wedging a 30 conductor or conductors in the grooves.

In practising my invention, I provide a longitudinal member in which a plurality of longitudinal grooves or troughs slope to the surface of said member to provide portions against which conductors may be wedgingly held. Members or rings, embracing the grooved member, are forced apart by a compression spring and bear against conductors to secure the same in position in 35 the grooves.

Figure 1 of the accompanying drawings is a longitudinal sectional view of a connector embodying my invention; Fig. 2 is an end elevational view thereof; Fig. 3 is a 40 transverse sectional view of the device shown in Fig. 1, and Figs. 4 and 5 are side-elevational views of the device shown in Figs. 1, 2 and 3, showing other arrangements of conductors connected thereto.

A member 1, which is preferably of hollow, cylindrical form but which may be solid and of other cross sectional form and constructed from brass, copper or other suitable material, is provided with longi- 50

tudinal grooves 2 that extend between and slope to points on the surface of, and removed from, the ends of the member 1.

Rings 3, preferably of rectangular cross-section, slidably embrace the member 1 and are forced apart, by a helical spring 4, toward lugs or stop members 5 at the ends of the member 1.

When the rings 3 are pressed toward each other, conductors 6 may be placed in the ends of the grooves 2, as shown in Figs. 1, 4 and 5. When the rings 3 are released, they are forced apart by the spring 4 to tightly wedge the conductors 6 against the sloping ends of the grooves 2. The device is extremely simple and durable in construction and economical to manufacture and facilitates the making of various forms and groupings of effective connections. 70

While I have shown and described a particular form of my invention, changes may 75 be effected therein without departing from the spirit and scope thereof, as set forth in the appended claims.

I claim as my invention:

1. A connector comprising an elongated 80 member having lateral projections at the ends thereof and a longitudinal channel extending between positions removed from the ends of the member, longitudinally-movable members embracing said member, and a 85 compression spring extending between said movable members for moving the same oppositely toward the ends of said elongated member and for forcing conductors against said elongated member at the ends of said channel, said projections limiting the movement of said movable members when the conductors are disconnected from said elongated member. 90

2. A connector comprising a cylindrical 95 member having a plurality of longitudinal conductor-receiving grooves extending between points removed from the ends thereof, longitudinally-slidable rings embracing said member, a helical spring embracing said 100 member between said rings to secure the conductors in position, and means for limiting the movement of said rings.

3. A connector comprising a tubular member having a longitudinal conductor-receiving groove extending between points removed from the ends thereof, longitudinally-slidable members mounted on said 105

- member and a helical spring embracing said tubular member between said slidable members.
4. A connector comprising a tubular member having a longitudinal conductor-receiving groove extending between points removed from the ends thereof, longitudinally-slidable members mounted on said member, a helical spring embracing said tubular member between said slidable members and means for limiting the movement of said slidable members.
5. A connector comprising an elongated member having a longitudinal conductor-receiving groove extending between points removed from the ends thereof, longitudinally-slidable members embracing said member and resilient means for pressing the slidable members toward the ends of the grooved member.
- 15 6. A connector comprising an elongated member having a longitudinal conductor-receiving groove extending to a position removed from one end thereof, a longitudi-

nally-slidable member embracing said member and resilient means for pressing the slidable member toward the said end of the grooved member.

7. A connector comprising a member having an elongated conductor-receiving channel therein, said channel having a portion sloping to the surface of said member, and a member movable along said surface in the direction of said channel to secure the conductor in position at the sloping portion of the channel.

8. A connector comprising an elongated member having a longitudinal conductor-receiving groove extending to a position removed from one end thereof, a longitudinally-slidable member mounted on said member and resilient means for moving the slidable member toward the said end of the grooved member.

In testimony whereof, I have hereunto subscribed my name this 28th day of Feb. 1919.

PAUL M. HENGSTENBERG.
